US0D1044079S

(12) **United States Design Patent** (10) Patent No.: **US D1,044,079 S**
(45) Date of Patent: ** Sep. 24, 2024

(54) **WALL LAMP**

(71) Applicant: **Guangzhou Zemi Electronic Technology Co., Ltd.**, Guangzhou (CN)

(72) Inventor: **Xiaoyan Liang**, Guangzhou (CN)

(73) Assignee: **Guangzhou Zemi Electronic Technology Co., Ltd.**, Guangzhou (CN)

(**) Term: **15 Years**

(21) Appl. No.: **29/889,454**

(22) Filed: **Apr. 12, 2023**

(51) LOC (14) Cl. **26-05**

(52) U.S. Cl.

USPC **D26/63; D26/87**

(58) **Field of Classification Search**

USPC D26/24, 61, 63, 65, 72, 85, 93, 106, 110,

D26/87, 92

CPC F21V 21/14; F21V 21/26; F21V 21/30;

F21S 8/00; F21S 8/003; F21S 8/03; F21S

8/033; F21S 8/04

See application file for complete search history.

(57) **CLAIM**

The ornamental design for a wall lamp, as shown and described.

DESCRIPTION

FIG. 1 is a front, right and top perspective view of a wall lamp, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the wall lamp that form no part of the claimed design.

1 Claim, 8 Drawing Sheets
